17 Claims. (Cl. 169—28)

This invention relates to improved devices for stoppering and opening fluid discharge orifices in fire extinguishing and other fluid pressure apparatus and systems.

5 The invention finds particular application in connection with automatic fire protection apparatus and systems and the object of the invention is to provide devices and apparatus adapted to contain corrosive acids as well as other fluids under pressure and to effect automatic discharge thereof at a high rate.

Water sprinkling apparatus comprising discharge devices capable of discharging fluid at a high rate generally incorporate valve devices forced onto seatings by struts, collapsible as the result of temperature rise. Such devices cannot operate before a fire has spread considerably and are unsuitable for containing fluids of a corrosive nature as these would corrode the valve seatings.

20 Containers for corrosive fluids are therefore provided with sealing discs clamped by screw caps or soldered over the container discharge orifice from which discharge is effected by piercing the discs with a piercing tool or plunger.

25 The orifice produced in the seal by such plungers is invariably ragged and torn edge portions may be bent across the discharge orifice by the discharging liquid. Consequently a rather slow and indeterminate rate of discharge may be produced. Moreover the forcing through the seals of the plunger and the return stroke thereof until it clears the discharge orifice results in a time lag or delay between the commencement of operation of the plunger operating mechanism and the commencement of discharge of the fire extinguishing liquid or gas.

30 The reduction of this time lag is of extreme importance in the case of automatically operating fire extinguishers for use upon aircraft in accidental crashes. In such crashes inertia forces burst the fuel tanks or fracture the fuel pipes and a dense fuel vapour or haze is created which, if ignited, envelopes the aircraft or wreckage in a sheet of flame which cannot be extinguished by the contents of a fire extinguisher of a size which is practical to carry upon an aircraft. Discharge of the contents of a fire extinguisher embodying a seal piercing plunger would invariably take place after ignition of the petrol vapor and 35 discharge from such devices is in any case too slow to extinguish a fire under such circumstances. It is one object of the invention to provide an improved form of stoppering and opening device for fluid containers and vessels.

40 Another object is to provide a brittle material

stoppering device for hermetically sealing fluid containers which is capable of fracture at a selected point to cause or permit discharge of the contents.

45 A further object of the invention is to provide mechanical and chemical means for opening the improved type of container stoppering device.

50 A still further object of the invention is to provide an improved mounting bracket for liquid containers whereby the insertion and removal of the container in the bracket is facilitated.

55 Yet another object is to provide improved hand operated means for effecting discharge of fluid containers.

60 Further objects of the invention are to provide fluid stoppering devices of a character which are positively prevented from leaking and which by fracture of the material are capable of effecting discharge of large volumes of fire extinguishing liquids in a short period.

65 With the above objects in view the invention consists in improved forms of liquid containers or water sprinkling system stoppering devices and certain combinations and arrangements of parts which will be hereinafter described and particularly recited in the claims.

70 With these and other objects in view, the invention will be better understood from the following detailed description taken in connection with the accompanying drawings wherein:

75 Figure 1 shows a fire extinguisher fluid container embodying the invention.

Figure 2 shows an explosive element.

80 Figure 3 shows a modification of the construction shown in Figure 1.

Figure 4 shows a further modification of the construction shown in Figure 1.

85 Figure 5 shows one form of the invention in sectional plan.

Figure 6 shows a side view of Figure 5 in partial section.

90 Figure 7 shows one application of the invention to sprinkler heads.

Figure 8 shows a modification of the construction shown in Figure 7 and

95 Figure 9 shows another modification of the construction shown in Figure 7.

Figure 10 shows the elements of the lower part of Fig. 1 on a larger scale.

100 Figure 11 is an assembled view showing one of my fire-extinguishing liquid containers mounted in the engine compartment of an airplane.

105 Figure 12 shows in elevation on a larger scale certain elements of the lower part of Fig. 1 in

cluding the tubular neck member and its stem carrying a flange.

Figure 13 shows in vertical section the tubular neck member and stem carrying a flange of Figure 12.

Figure 14 is a vertical sectional view as in Figure 13 showing the fuse element held in place by the flange and retaining ring.

Figure 15 is a top plan view partly in section taken on the line 15-15 of Figure 13.

Figure 16 is a horizontal sectional view taken on the line 16-16 of Figure 13.

Figure 17 is a fragmentary sectional view taken on the line 17-17 of Figure 13 showing a detail of the interlocking slot in neck member 17.

Figure 18 is a view partly in section taken on line 18-18 of Figure 13 showing the flange with its slot through which the lead wires pass.

Referring to Figure 1 of the drawings numeral 20 2 represents a fire-extinguisher container and numeral 3 a channel-shaped mounting bracket therefor, one end of which is provided with an abutment for container 2, the other end carrying a junction-box form of device for connecting 25 the discharge orifice end of the container to discharge tube 6 terminating near the engine of a vehicle or craft or at other fire danger sources.

A strap 4 clamps container 2 in bracket 3 and the container is provided with a handle for withdrawal from the mounting bracket and for hand operation.

The container is provided with a cup-shaped tubular neck member 7 cast or machined from solid material adapted to be soldered, brazed or 35 welded to container 2. Member 7 comprises a flange 8 secured by a stem-like projection 54 to what may be termed the bottom 55 of member 7 and forming a groove 9 between flange 8 and the bottom 55 of member 7. The stem 54 from 40 flange 8 is integral as shown in Figure 1 with member 7 and is of less diameter than the bore or hole in this member so that a thin-walled rim 56 is formed at the junction of these parts which is easily fractured by force-applying means 45 as fracture is produced by shearing of the material, and an exceptionally large-diameter fluid-discharge orifice is produced by such fracture for containers of this character.

Owing to the fact that member 7 and flange 50 8 are integral, no risk exists of corrosion or mechanical damage of the discharge orifice parts and yet flange 8 and its stem are easily fractured by ignition of a small fuse or explosive element 10 connected by leads 11 to a pair of spring contacts 12 of the character used as jacks in 55 telephone apparatus and adapted to be engaged by a plug 13 as also used in such apparatus. Contacts 12 are conveniently carried by flange 8 and plug 13 is secured to box 5 by a screwed 60 sleeve.

The fuse element 10 may contain fine-grain gunpowder enclosed in a moisture-proof sleeve 14 as shown in Figure 2. Sleeve 14 contains the powder and a fuse 15 connected by insulated leads 11 65 to contacts 12 passes through a slot 60 of suitable size in flange 8. If the sleeve and the covering of leads 11 are of rubber these can be vulcanized together at points 16 to form a moisture-proof element.

To facilitate fitting of the resilient sleeve 14 into 70 groove 9 a ring 17 is provided for slipping over flange 8 after the leads 11 have been positioned in the slot in flange 8, the ring being gradually worked down onto a seat 18 formed in member 75 7. A projection 61 from ring 17 passes into a

slot 59 in fitting 7 and a screwed sleeve 19 is finally screwed onto member 7 by screw threads 58 over ring 17 forming a discharge nozzle for the container.

Junction box 5 is provided with a non-return 5 resilient valve seating or washer 20 clamped to box 5 by a screw cap 21. Sleeve 19 is shaped so as to fit into washer 20 tightly to prevent leakage of fluid during discharge and to facilitate withdrawal of the container. An extended flange 10 or rib 22 is formed integral with or secured upon sleeve 19 and is adapted to contact with cap 21 whereby leverage is produced for withdrawing the container from the bracket and the junction box, for example, for hand use. 15

To prevent escape of explosive gases groove 9 is filled with hard setting plastic substance and this enables a comparatively small amount of explosive substance to fracture neck 7 at the bottom of groove 9 when ignited, the orifice produced being free from ragged edges and other obstructions. Flange 8 and the stem portion forming the bottom of groove 9 is blown through sleeve 19 which is expanded at 23 to permit escape of the liquid immediately after fracture of the material at the bottom of groove 9. 20

The container 2 is automatically connected to and disconnected from a source of igniting currents by plug 13 when container 2 is inserted within and withdrawn from bracket 3. The 30 source may be an aircraft or vehicle battery controlled by a manually operated switch 61 or by a crash-operated switch 62 or by one of a number of flame or temperature sensitive switches 63.

The extinguisher is generally mounted in the 35 cockpit in an aircraft or near the driver's seat in a vehicle. To permit hand operation a projection 24 provided with a pip 25 of brittle material extends from member 7, a projection 26 of reduced diameter being soldered into a hole in extension 24 leaving a gap which permits fracture of the pip at projection 26. A small orifice 29 is provided in pip 25 and in extension 24 which prolongs the period of discharge of the container to permit an operator reasonable time to play 40 the projected stream of fire-extinguishing substance upon a fire. 45

To prevent accidental fracture of pipe 25 and at the same time to facilitate its fracture by hand when desired a sleeve 27 fits fairly tightly, but 50 slidably, upon extension 24 and this protects parts 25 and 26. When hand operation is desired sleeve 27 is pulled forward to stop ring 28 thereby extending the overall length of the parts and providing leverage for breaking pip 25 by the 55 fingers of one hand without appreciable effort while the extension is projecting towards a fire ready to play thereon.

Container 2 is provided with a charging plug 60 socket 200 hermetically secured to the container wall. A plug 201 screws into the socket and a tenacious material ring 202 is soldered or sweated to the socket to hermetically close the container after charging and applying pressure to the contents. 65

As will be clear, flange 8 carrying spring contacts 12 is blown into the bottom of box 5 and the contacts usually crumple up but cushion the blow although damage may be caused to plug 13. Moreover contacts 12 may short circuit the plug 70 and to prevent damage thereby a fuse 131 is provided in the handle of plug 13 which may or may not be blown. In any case after operation of the extinguisher the container is replaced by another charged container and a new plug 13 is 75

fitted, the discharged container being refitted with a new member 1 and associated parts.

Figure 11 shows one of my fire-extinguishing liquid containers mounted in the engine compartment 66 of an airplane 65. The engine 67 drives propeller 64, and its carburetor 68 is supplied with fuel by fuel line 69 from fuel tank 88.

In a modification of the above described construction shown in Figure 3 a plug device 38 is adapted to be screwed into the neck of a fluid container 2, being soldered thereto round the upper edge at 32. A disc 33 of tenacious material is soldered, brazed or welded to the orifice of plug 38 projecting over a groove formed therein and housing a fuse element 34 capable of ignition by means of plug-in pins 35. The disc 33 may be provided with a strengthening ring 36 and element 34 is preferably set in plastic substance consisting of rubber compound adapted to be slightly dissolved and setting firmly.

Element 34 may be an explosive device but may also be made of a material which when ignited produces sufficient heat to soften the soldered joint between disc 33 and plug 38 so that the expansion of the ignited mass can force the seal away from the discharge orifice permitting discharge through nozzle 31. To permit hand operation a plunger 37 is fitted in an extension of plug 38, being normally held against a seat by a spring 38 which is compressed to permit piercing of disc 33 when plunger 37 is struck upon the ground, for example.

In Figure 4 is shown a still further modification of the invention. A fluid container 2 is provided with an integral neck fitted with a threaded nut 40 forming a chamber for heating material 41 enclosed in asbestos 42 on three sides but in direct contact with a thin tubular wall of the neck of the container on the other side. A plug 43 is fitted in the neck and a fuse 44 serves to ignite material 41. A tubular nozzle 45 fits over the neck and upon ignition of material 41 the thin wall becomes heated to a point enabling nut 40 to fracture the wall due to expansion of the heating substance, plug 43 preventing contact of fluid with the wall and collapsing thereof due to pressure exerted by material 41 when energized.

The apparatus of the present invention is of particular use in preventing outbreaks of fire in the case of aircraft crashes. When an aircraft is subject to an impact sufficient to cause serious and extensive damage thereto, switch 62 operates to close the circuit for the battery igniting the explosive or heat-producing charge, to remove the stoppering devices, and to produce a discharge orifice of sufficient size to permit ejection of the contents of container 2 within 1 to 5 seconds after the moment of impact.

The apparatus also operates automatically when a fire breaks out upon an aircraft or a vehicle if stationary or during flight or movement. In this case heat-sensitive switching device 63 closes the circuit for the battery and ignites element 10. If the pilot or driver observes a fire which has not reached switches 63 he can cause operation by closure of switch 61.

A modification of the invention is shown in Figures 5 and 6 in which a fluid discharge orifice 50 is fitted with a nozzle sleeve 51 adapted to form a journal support for eccentric cams 53. These cams are disposed in groove 9 and engage flange 8 when rotated by an operating handle 54 and sever the flange and its stem from the discharge orifice.

While primarily intended for manual opera-

tion handle 54 may be actuated by any suitable form of automatic operating mechanism when a fire breaks out.

The application of the invention to automatic sprinkler heads is shown in Figures 7, 8 and 9 in which numeral 70 represents a fluid or water supply pipe to which is screwed or otherwise secured a tubular member 71 provided with a flange or disc 75 and groove 9 fitted with a fuse or explosive element 10. In Figures 7 and 8 the fuse or explosive element is enclosed by a sleeve 72 carrying a pair of arms 73 which carry a water-deflecting device 74 disposed immediately above the discharge orifice.

In the case of the construction disclosed in Figures 7 and 8, ignition may be effected by impact or flame and heat-sensitive switches over cable 76 or by direct ignition of an inflammable cap 77 which ignites a fuse connected to element 10.

In the construction shown in Figure 8 the disc 75 may be cup-shaped or provided with flanges and when subjected to flame or heat it melts the soldered joint by which it is secured to member 71. To prevent loss of heat by conduction an inefficient conductor of heat such as a cup-shaped rubber element 78 is inserted in the discharge orifice and adhesively secured to disc 75. To prevent loss of heat by conduction to pipe 70 member 71 is screwed thereto by a heavily red-leaded joint which prevents escape of fluid as well as conduction of heat.

The construction disclosed in Figure 9 is operated by temperature rise alone, a bimetallic strip 79 normally retaining a percussion hammer 80 in the position shown in full lines against the action of spring 81. When a predetermined temperature rise takes place strip 79 releases hammer 80 which is swung into the position shown by dotted lines, thereby igniting element 10 by percussion cap 82.

One side of the explosion chamber is formed by a ring 86 screwed onto member 71. Strip 79 is carried by a cup-shaped cover 83 carrying an adjusting screw 84 by which the temperature at which ignition takes place can be regulated within limits. Cover 83 may be screwed to flange 8 and the parts carried by the flange are removed thereby. When ignition occurs a whirling disc 85 which is mounted in the discharge nozzle produces a spreading of the emitted fluid stream.

The sprinkler device according to the invention does not have a valve seat and can be operated by extremely sensitive remote control devices or by equally sensitive devices subject to direct influence as desired. Moreover by setting the fuse or explosive element in a hard setting, plastic compound or substance, the active elements will remain active for very many years and, of course, no possibility of leakage of water or of chemical fire extinguishing fluid exists.

Having thus fully described my invention, what I claim as new and desire to protect by Letters Patent is:

1. A stoppering device for a fluid container, circumferential sides and a disc-shaped end to said device, a flanged stem of lesser diameter than the bore of the device secured to said disc-shaped end, and means for severing said stem from said disc-shaped end by shearing of the material.

2. A fluid container, a cup shaped stoppering device hermetically sealed in said container, a stem provided with a flange integral in the bottom of said cup shaped device, a fuse element fitted between said flange and the cup-shaped device, a sleeve device adapted to confine said

- fuse element below said flange, and means for igniting said fuse element to effect severance of the flanged stem from the cup-shaped device.
3. In the combination according to claim 2, a ring fitting over said flange and fuse element and secured against rotation by engagement with said cup shaped device.
4. A fluid container, a cup-shaped stoppering device in said container, a stem provided with a flange integral with said device, an explosive element confined below said flange, electric current leads to said element, contact members carried by said flange for said leads, and a contact plug for engaging and disengaging said contact member.
5. A fluid container, a cup-shaped stoppering device for said container incorporating a stem provided with a flange, a mounting bracket for said container, a junction-box form of device secured to said bracket, an outlet from said junction box to liquid-utilization points, a resilient washer secured by a cap device to an open side in said junction box, a sleeve device secured over the flanged stem and engaging said washer to form a liquid-tight joint, and a flange upon said sleeve adapted to contact with said cap device and to provide leverage for withdrawing the sleeve from the washer.
6. A fluid container, a cup-shaped stoppering device provided with an integral flanged stem, an explosive device between said cup shaped device and flanged stem, a ring surrounding said explosive device, a sleeve secured to said cup-shaped device and enclosing said ring and explosive device, a mounting bracket for said container, a junction box upon said mounting bracket, an outlet from said junction box, an inlet to said junction box, a resilient washer secured by a screw cap in said inlet, a flange on said sleeve, and an abutment for said flange on said junction box.
7. In the combination according to claim 6, spring contacts carrying leads for said explosive device and mounted upon said flanged stem, a contact plug secured in said junction box engageably with said spring contacts, an electric igniting current source, and circuits comprising switch control means connecting said source to said plug.
8. A container, a cup-shaped stoppering device in said container, a tubular extension from said device, a frangible pip secured in said extension, and means for severing said pip to produce a discharge orifice in said stoppering device.
9. In the combination according to claim 8, a protecting sleeve fitted upon said tubular extension, and means for pulling said sleeve onto said frangible pip to facilitate its fracture.
10. In a craft, a power unit, a fire-extinguishing fluid container, a cup-shaped stoppering device in said container comprising an integral closure portion adapted when severed from said device to provide an outlet from the interior of said device, means for severing said integral portion of said cup shaped device, and means for conducting fire-extinguishing fluid from said container to said power unit.
11. In a craft, a power unit, a fire-extinguishing fluid container, a cup-shaped stoppering device in said container, a flanged integral stem in said cup-shaped device, an explosive element posi-

tioned between said flanged stem and said cup-shaped element, means for confining said explosive element below said flange, automatic means for igniting said explosive element to sever said flanged stem to produce an orifice in said cup-shaped member, and means for conducting fire extinguishing fluid from said cup-shaped member to said power unit.

12. In a stoppering device for a fluid container, a tubular member secured to said container, a flanged closure element for said member hermetically secured thereover, an abutment associated with said tubular member and forming with the flange upon said element a groove near the end of said member, and means disposed in said groove for severing said closure member from said tubular member.

13. In a stoppering device for a fluid container, an integral cup-shaped element hermetically secured to said fluid container, a shoulder formed on the closed end of said element, said shoulder having a terminal flange forming a groove with said element, and means disposed in said groove for severing said shoulder from the end of said element to produce an orifice therein.

14. In a stoppering device for a fluid container, an integral cup-shaped element secured to said container, a flanged shoulder formed on the closed end of said element and being of less diameter than the bore of said cup-shaped element, the integral rim portion of the closed end of said cup-shaped element intermediate the longitudinal surface thereof and said shoulder being relatively thin, and means for fracturing said rim portion in shear.

15. A stoppering device for fluid containers comprising in combination, an integral cup-shaped element hermetically secured to said container, the closed end of said cup-shaped element being recessed to form a shoulder portion, a projecting flange formed on said shoulder portion and forming with said element a groove, explosive substance positioned in said groove, means for retaining said substance in said groove, and means for igniting said substance to sever the flanged shoulder from the end of said element to produce an orifice therein.

16. A discharge device for fluid containers comprising in combination, a cup-shaped element secured to said container, a flanged shoulder formed on the closed end of said element and forming with said element a groove, a sleeve device secured to said element and enclosing said groove, means in said groove for severing said shoulder from the closed end of said cup-shaped element to produce an orifice therein, and means for conducting the fluid from said orifice to a point of utilization.

17. A tubular fluid discharge member having a terminal shoulder portion, a stem projecting from and centrally attached to said shoulder portion and readily separable therefrom, said stem being provided with a terminal flange, an explosive element surrounding said stem and retained between said shoulder and said flange, means for igniting said explosive element, and fluid stream deflecting means disposed in the path of the jet of liquid discharged from said discharge member when said stem is separated from said discharge member.

HUBERT MACKENZIE SALMOND.
